Cleveland, Ohio, assignors to William Thomas,
Cleveland, Ohio

Application October 15, 1945, Serial No. 122,834

Term of patent 7 years

(Cl. D34—15)

To all whom it may concern:

Be it known that we, Salvatore J. Lamancusa and Patsy G. Catanzarite, citizens of the United States, residing in Cleveland, in the county of Cuyahoga and State of Ohio, have invented a new, original, and ornamental Design for a Figure Toy, of which the following is a specification, reference being had to the accompanying drawing, forming a part thereof, in which:

Fig. 1 is a side elevation of the figure toy embodying our new design;

Fig. 2 is a top plan view thereof; and

Fig. 3 is a front elevation of the figure toy.

We claim:

The ornamental design for a figure toy, substantially as shown.

PATSY G. CATANZARITE,
SALVATORE J. LAMANCUSA.
